UNITED STATES PATENT OFFICE.

HARVEY M. NICHOLLS, OF SAN FRANCISCO, CALIFORNIA.

VEHICLE-ELEVATOR.

No. 839,185.

Specification of Letters Patent.

Patented Dec. 25, 1906.

Application filed February 5, 1906. Serial No. 299,634.

To all whom it may concern:

Be it known that I, HARVEY M. NICHOLLS,
a citizen of the United States, residing at
San Francisco, in the county of San Fran-
5 cisco and State of California, have invented
certain new and useful Improvements in
Vehicle-Elevators; and I do hereby declare
the following to be a full, clear, and exact de-
scription of the invention, such as will enable
10 others skilled in the art to which it apper-
tains to make and use the same.

My invention relates to vehicle-elevators.

The prime objects of my invention are to provide a simple, inexpensive, and durable device by means of which vehicles of every size and variety can be readily and easily elevated sufficiently to enable the wheels thereof to turn free from the ground for purposes of washing, painting, repairing, or other manipulation.

The locking and retaining of the device in the elevated position is accomplished automatically, while the lowering is accomplished by the releasing of a simple ratchet and the vehicle brought to the ground without the least danger of jarring.

In carrying out my invention I have not overlooked the requisites of economy in the cost of manufacture and have provided a device which will appeal to stablemen, carriage and wagon painters, and manufacturers and owners of vehicle-repositories.

The invention more particularly resides in the novel combination, construction, and arrangement of parts, all as more fully hereinafter described, and set forth in the claims and illustrated in the accompanying drawings, in which—

Figure 1 is a side elevation of the complete device, the broken lines indicating the position of the members when elevated. Fig. 2 is a top view. Fig. 3 is a transverse section taken on the line X-X of Fig. 1.

In the drawings, A and A' represent side pieces suitably united into a rigid structure by the braces B and forming a base to support the elevator-carriage E. The base is provided with the respective front and rear inclines C' C, on which the respective front 45 and rear wheels D' D of the elevator-carriage 50 E are adapted to run. The rear inclines or tracks C are made considerably flatter than the front inclines for the purpose hereinafter to be described. The top side bars or bed of the elevator-carriage E extend forward of the front wheels D', as shown at E''. The length 55

of these extensions E'' depends on the size of the elevator or the length of the body of the vehicle or vehicles to be lifted.

On the top of the elevator-carriage and 60 near its rear end are the pivoted bars I, which may be turned so as to have their outer ends extend more or less above the level of the top of the elevator and held in position by suitable means, as the crowbar a. Normally 65 the elevator will rest with the wheels D' D at the foot of the respective inclines C' C. The elevator is adapted to be held and locked at any suitable point on these inclines by appropriate means, as the pawl-lever F, which is hinged to and carried by the elevator-carriage and is adapted normally, when the elevator is being lifted, to ride loose over a fixed 70 stop-bar G.

In operation the hinged bars or stops I are 75 adjusted to the proper height and held there by suitable means, as the cross-bar *a*, so that when the wagon is backed over the elevator, as is contemplated by the present invention, the rear axle of the vehicle, which, as well 80 known, is usually higher from the ground than the front axle, will come in contact with the stops I close to their raised ends and approximately over the axle of the wheels *D* of the elevator-carriage. Sufficient momentum 85 being given to the vehicle in backing it over the elevator, the latter as soon as the hinged stops I are engaged by the rear axle will move along with the vehicle, gradually lifting the rear wheel of the vehicle clear of the 90 floor or ground. It is not intended that the carriage shall engage the front axle of the vehicle simultaneously with the lifting of the rear wheels of the vehicle. It is therefore manifest that with the wheels *D* running up 95

the relatively flat inclines C the power necessary to lift the rear end of the vehicle is comparatively slight and is scarcely appreciable. The more abrupt front inclinations C', on which the front rollers D' of the elevator-carriage run, simply serve to bring the elevator in contact with the front axle of the vehicle and lift the front end of the vehicle when the rear wheels of the vehicle have been sufficiently elevated from the ground. It is to be understood that the amount that a vehicle is to be lifted is very slight, being just sufficient to enable the wheels to revolve or to be taken off. Most of the lifting is done by running up the flatter rear incline, and the final lift on the front axle is done quickly and done easily by reason of the momentum al-

- ready attained by the moving parts. The pivoted stop-bars I are made adjustable, so as to dispose them always in proper operative relation with respect to the rear axle of the vehicle to be elevated, and so throw the weight at the most advantageous point on the elevator. The rack-arm F having been released from the keeper H and being carried along by the moving elevator rides over the stop G until the elevator and vehicle are brought to a standstill, whereupon the teeth in the rack engage the stop G and hold the carriage and vehicle in appropriate elevated position. The latter can now be washed to good advantage, repaired, greased, painted, or otherwise manipulated at will. When it is desired to let the vehicle down, it is only necessary to give a slight lift on rack F to disengage the stop G, the rack being caught and held in the hook H. A guide strap or bar J is arranged over the front axle of the elevator-wheels D and parallel with the inclines C and is for the purpose of preventing the back end of the elevator kicking up in case the front axle of the vehicle engages the elevator so far on the front side of the front wheels D' as to unbalance the elevator. The guide-bar J keeps the wheels of the elevator on their tracks all the time.
- In the actual use of a machine built and operated according to the foregoing description and the accompanying drawings I have found all of the advantages above enumerated, one man being able to lift a heavy wagon entirely clear of the ground.
- It is possible that various modifications and changes may be made in construction without departing from the principle of the invention.
- Having thus described my invention, what I claim, and desire to secure by Letters Patent, is—
1. A wagon-lift comprising two inclined trackways, an elevator-carriage having front and rear wheels running on said trackways, the front wheels running on the one track and the rear wheels thereof on the other, and means carried by the carriage for locking and holding the latter at any desired point.
  2. A vehicle-elevator consisting of two inclined roadways, a frame provided with forward and rear wheels, said forward wheels being arranged to rest on one of said roadways while the rear wheels rest on the other roadway, and means for automatically retaining said frame at various points relative to said roadways.
  3. A vehicle-elevator comprising two inclined roadways of relatively different pitch, and a carriage mounted to travel simultaneously on both of said trackways.
  4. A vehicle-elevator comprising two inclined roadways of relatively different pitch, a carriage mounted to travel simultaneously

on both of said trackways, and means operative by the movements of the carriage for locking the latter at different points along said roadways. 65

5. A vehicle-elevator comprising two inclined roadways of relatively different pitch, 70 a carriage mounted to travel simultaneously on both of said trackways, means operative by the movements of the carriage for locking the latter at different points along said roadways, said last-named means comprising a 75 hinged rack-bar on the carriage, and a fixed stop engageable by the rack-bar.

6. A vehicle-lift comprising an incline support, a carriage movable on said support and operative by the vehicle to be elevated, and 80 means carried by the carriage for automatically holding the carriage at different elevations.

7. A vehicle-lift comprising an incline support, a carriage to travel on the incline of 85 said support, said carriage having an adjustable stop engageable by the vehicle to be lifted and adapted to cause said carriage to move with the vehicle, and means for automatically holding the carriage at different 90 elevations.

8. A vehicle-lift consisting of forward and rear inclined roadways, said roadways being of relatively different pitch, a frame provided with forward and rear wheels, said wheels being arranged to travel on said respective roadways, and adjustable hinged stop-bars carried by the frame and arranged to be adjusted in elevation relative thereto. 95

9. A vehicle-lift consisting of forward and rear inclined roadways, said roadways being of relatively different pitch, a frame provided with forward and rear wheels, said wheels being arranged to travel on said respective roadways, and adjustable hinged stop-bars carried by the frame and arranged to be adjusted in elevation relative thereto and disposed on the frame adjacent to the roadway which is of flatter pitch. 100

10. A vehicle-lift consisting of forward and rear inclined roadways, said roadways being of relatively different pitch, a frame provided with forward and rear wheels, said wheels being arranged to travel on said respective roadways, adjustable hinged stop-bars carried by the frame and arranged to be adjusted in elevation relative thereto and disposed on the frame adjacent to the roadway which is of flatter pitch, and means for automatically retaining the frame at various elevations 115 on the roadways. 120

In testimony whereof I have hereunto signed my name to this specification in the presence of two subscribing witnesses.
